UNITED STATES PATENT OFFICE.

JOSEPH S. WOOD, OF BROOKLYN, NEW YORK.

GAS-MACHINE.

SPECIFICATION forming part of Letters Patent No. 288,752, dated November 20, 1883.

Application filed August 28, 1883. (No model.)

To all whom it may concern:

Be it known that I, JOSEPH S. WOOD, of Brooklyn, in the county of Kings and State of New York, have invented certain new and 5 useful Improvements in Gas-Machines, of which the following is a specification.

This invention has reference to an improved machine for making gas from naphtha or other light hydrocarbon oil by means of heat, and it 10 is designed especially with a view to furnish a cheap and simple apparatus for steamboats, railroad-cars, and other purposes where a small number of burners is to be supplied; and the invention consists of a generating-retort 15 which is heated by a vapor-burner and supported by oil-supply and gas-conducting pipes at opposite sides of the burner. The gas-conducting pipe is connected to a mixing-chamber, which is provided with a needle-valve 20 and an adjustable injection-throat, as will more fully appear hereinafter, and finally be pointed out in the claim.

In the accompanying drawings, Figure 1 represents a vertical longitudinal section of my 25 improved gas-machine, and Fig. 2 shows the arrangement of the oil-tank below the body of a car.

Similar letters of reference indicate corresponding parts.

30 A in the drawings represents a hollow supporting-stand, to which the oil-supply pipe B is connected. The oil is supplied under pressure through the hollow stand A to a generating-retort, C, which is supported by pipes E E', 35 which communicate with openings *a a* in the ends of the retort. The pipe E communicates with the hollow standard, and supplies the oil to the retort C. The pipe E' conducts the vapors generated in the retort to a burner, D, 40 and to a mixing-chamber, F, by a connecting-pipe, E''. The burner D is interposed between the hollow standard A and the pipe E', and connected with the latter by a small supply-orifice.

45 The burner D is provided with a needle-valve, D', the tapering end of which serving to open or close the tapering gas-supply orifice *e*' of the valve-chamber D'', so that the heating-flame of the burner may be enlarged 50 or diminished, according to the quantity of gas to be generated.

The burner D is provided in the usual man-

ner with an air-port, *e*², to supply the quantity of atmospheric air that is required for the combustion of the vapors.

55 The mixing-chamber F is provided with a needle-valve, G, and valve-chamber G', the needle-valve being adjusted in the usual manner in a stuffing-box of the chamber G', so as to open or close the tapering orifice that leads 60 into the mixing-chamber F.

The mixing-chamber F is provided with an air-port, *i*, and with an injection-throat, F', that is connected to the gas-supply pipe which 65 leads to the burners.

The mixing-chamber can be enlarged or diminished in size by adjusting its inclosing-tube up or down on the threaded end of the valve-chamber G', so that the proper proportion of atmospheric air is supplied to and 70 mixed with the vapors in the mixing-chamber, whereby the lights are prevented from smoking.

In case the gas-machine is used in a railroad-car, an oil-tank, H, is stored beneath the bottom 75 of the car, and the machine arranged in suitable position in the gentlemen's wash-room. The oil-supply pipe H' of the tank is provided with a valve having a weighted lever, H², as shown in Fig. 2, so that in case of accident and up-setting of the car the valve will be automatically closed, and thereby the supply of oil to the gas-machine automatically interrupted. The gas-machine is started in the same manner as other gas-machines having generating- 80 retorts heated by a burner by lighting alcohol in a cup or dish below the burner. This heats up the oil in the adjoining oil-supply pipe at one side of the burner, and supplies vapor to the burner, which then heats the retort.

85 As soon as the generating-retort is sufficiently heated, the oil in the same is changed into vapors, which are then supplied to the burner and to the mixing-chamber, the needle and injection-throat of which are properly adjusted, according to the quantity of gas required to the burners.

90 The gas-machine thus obtained is of extreme simplicity, and can be furnished at very low rates, so that it is specially adapted for steam-boats, railroad-cars, and other purposes in which a smaller number of burners has to be supplied. The heating-flame of the retort may 95 also serve as an illuminating-flame for a room

in which the gas-machine is located. By closing the needle-valve of the burner the operation of the apparatus is instantly interrupted, while by the needle-valve and the adjustable 5 injection-throat of the mixing-chamber the proper functioning of the same is fully controlled.

Having thus described my invention, I claim as new and desire to secure by Letters Patent—
10 The combination of a generating-retort, C, supported by upright pipes E E', a heating-burner, D, located between said pipes and connecting to the gas-conducting pipe E', an oil-

supply pipe, B, communicating with the pipe E, a conducting gas-pipe, E², and a mixing-chamber, F, having a needle-valve, G, and adjustable injection-throat F', substantially as and for the purpose set forth.

In testimony that I claim the foregoing as my invention I have signed my name in presence 20 of two subscribing witnesses.

JOSEPH S. WOOD.
